UNITED STATES PATENT OFFICE.

JOSEPH MEADWAY, OF BUFFALO, NEW YORK.

DEVICE FOR SECURING CHIMNEYS TO LAMP-BURNERS.

SPECIFICATION forming part of Letters Patent No. 436,069, dated September 9, 1890.

Application filed March 1, 1890. Serial No. 342,253. (No model.)

To all whom it may concern:

Be it known that I, JOSEPH MEADWAY, a citizen of the United States, residing in Buffalo, in the county of Erie and State of New York, have invented certain new and useful Improvements in Devices for Securing Chimneys to Lamp-Burners, of which the following is a specification.

The object of my invention is to produce a simple and efficient means for securing a lamp-chimney to a burner so that it cannot be accidentally removed or thrown off; and its construction and operation will be fully and clearly hereinafter described and claimed, reference being had to the accompanying drawings, in which—

Figure 1 represents a side elevation of a lamp, lamp-burner, and chimney, showing my improved device attached to the chimney and to the burner for holding the same firmly in place. Fig. 2 is a top view of the chimney-holder detached from the burner, showing it open, so that a chimney may be put in and fastened and the device secured to a burner at the same time. Fig. 3 is also a top plan view showing a horizontal section through a chimney in or about line *a b*, Fig. 1, and the chimney-holder securely fastened to it.

In said drawings, 1 represents an ordinary lamp, 2 the burner, and 3 the chimney.

The fastening device consists of a removable open ring 4, made preferably of spring-brass, but any other suitable material may be used.

The top edge of the ring may be ornamented, substantially as shown at 5, Fig. 1, or the top may be left plain, as shown in Figs. 2 and 3.

The open ends are each provided with a forwardly-projecting portion 6 and 6^a. The portion 6^a is provided with a hole sufficiently large to allow the screw 7 to slip easily back and forth therein, and the portion 6 is provided with a screw-threaded hole adapted to

engage with the screw-thread on the screw 7, so that by turning the screw by means of the 45 thumb-piece 8 the space within the ring may be either enlarged or contracted, according to the direction in which the screw is turned.

At the bottom of the ring 4, on its periphery, is a series of hook-shaped pieces 9 for 50 fastening the device to a burner. In Fig. 1 I have shown these hook portions 9 so located as to require four, but three may be used, as shown in Figs. 2 and 3, or more or less than the number shown.

In using this device it is placed on a burner so that the hook portions will catch over the top edge 10 of a burner. (See Fig. 1.) Then the chimney is inserted and the screw 7 is turned so as to draw the ring close and tightly to the 60 chimney, substantially as shown in Fig. 3. At the same time the chimney is tightened in place the hook portions 9 are drawn over the top edge of the burner, as shown in Fig. 1, so that the chimney is held rigidly to the 65 holding device and the holding device is simultaneously secured rigidly to the burner. There is no danger of the heat causing the glass to break within the ring, because the brass ring also takes the heat and expands 70 substantially with the glass of which the chimney is composed.

I claim as my invention the following:

A lamp-chimney holder consisting of a removable open spring-ring 4, provided with forwardly-projecting portions at the open ends, and a screw for drawing them together for rigid attachment to a chimney, in combination with a series of rigid hooks curving outward and inward from the lower edge of the 80 ring for simultaneous rigid attachment to a lamp-burner, substantially as described.

JOSEPH MEADWAY.
